UNITED STATES PATENT OFFICE.

LYMAN MIDDLEDITCH, OF NEW YORK, N. Y.

SHEET-FEEDING MACHINE.

1,176,079.

Specification of Letters Patent. Patented Mar. 21, 1916.

Application filed June 24, 1912. Serial No. 705,361.

To all whom it may concern:

Be it known that I, LYMAN MIDDLEDITCH, a citizen of the United States, and a resident of New York city, in the county of New York and State of New York, have invented certain new and useful Improvements in Sheet-Feeding Machines, of which the following is a specification.

The present invention relates to sheet separating and feeding machines and has more particularly reference to a sheet combing device.

The main object of the invention is to produce means for efficiently and quickly separating and feeding sheets to a printing or other machine.

Another feature of the invention resides in the means for lifting and lowering the combing wheel or sheet feeding device consisting in a lifting actuator which exerts a constant lifting force upon the combing device, and a timed mechanism which normally controls the lifting actuator aforesaid, together with a sheet actuated device which releases the connection between the timed actuating mechanism and the lifting actuator to permit the latter to become operative to lift the combing device quickly. This timed mechanism preferably tends to both raise and lower the combing wheel at predetermined intervals, and tends to restrain the lifting actuator until the advancing sheet breaks the connection between the timed mechanism and the lifting actuator to raise the combing wheel ahead of the time which it would otherwise be raised by the timed mechanism. Suitable means are also provided for restoring the broken connection between the timed mechanism and the lifting actuator aforesaid.

In order to break the connection between the timed mechanism and the lifting actuator when the sheet is to trip the combing wheel, it is preferred to utilize a fulcrum member or abutment against which a rotating member, carried by the releasable connection, acts to disengage or break the connection aforesaid. In the more specific form here disclosed, the advance of a sheet positions a filling member in the path of a constantly rotating member. The said rotating member is mounted on a pivoted lever or connection so that when the said rotating member has moved the filling member

into contact with the stationary abutment 55 member, the further rotation of the rotatable member serves to move the said lever or connection around its pivot to thereby disengage it with respect to another member, whereby the connection between the 60 timed mechanism and the lifting actuator is broken, for the time being, so as to permit the latter to act quickly to lift the combing wheel.

In the art as heretofore practised, it has 65 been customary to mount the combing wheel at the end of pivoted frames and to raise both the combing wheel and frame when it is desired to disengage the said combing wheel from the bank or pile of sheets. 70

One feature of the present invention consists in lifting the combing wheel in the frame which supports it without lifting the said frame. In this way the work which the moving parts are called upon to do in 75 disengaging the combing wheel from the pile or bank is much less than if the whole frame is raised. In connection with this feature, means are provided for temporarily supporting the combing frame so that it will 80 not turn on its pivotal support while the combing wheel is being lifted.

Preferably an eccentric bushing is employed for raising and lowering the combing device with respect to the sheet support, 85 which eccentric bushing is shifted intermittently. As disclosed herein, the said combing wheel is mounted on the eccentric bushing and this eccentric bushing is rocked intermittently by suitable means, such as by 90 the timed mechanism, or by means of the auxiliary lifting actuator, which latter in the present case takes the form of a spring. In connection with the foregoing suitable means are provided for rotating the combing wheel irrespective of the position of the eccentric bushing. So far as this and certain other features of the invention is concerned, it is of course immaterial whether or not the combing wheel feeds the sheets 100 rearwardly or forwardly. It is preferred when turning the eccentric bushing to so lift the combing wheel, that it turns in the direction of movement of the sheet so as not to move the sheet away from the position to 105 which it has been fed.

Numerous other features of construction, combination of parts and arrangement of

elements will appear as the specification proceeds.

In the accompanying drawings the invention is shown in a concrete and preferred form but changes of construction may of course be made without departing from the legitimate and intended scope of the invention as expressed in the annexed claims.

In the said drawings: Figure 1 is a top plan view of the forward section of the machine. Fig. 2 is a top plan view of the rear end of the machine, showing more particularly the combing device. By placing Figs. 1, and 2 together, a complete plan view of the machine is obtained. Fig. 3 is a side elevation of the intermediate section of the machine shown in Fig. 1. Fig. 4 is a view in elevation of the gearing from the gear side of the machine, that is the side opposite to that shown in Fig. 3, showing the gearing for transmitting motion to the intermediate section and rear end of the machine. Fig. 5 is a side elevation of the rear end of the machine, shown in Fig. 2. By placing Figs. 3 and 5 alongside each other, a complete view in side elevation of the machine may be had. Fig. 6 is a transverse sectional view on the line 9—9 of Fig. 3. Fig. 7 is a detail view of the drive for the combing wheel. Fig. 8 is a longitudinal sectional view of part of the machine adjacent to the combing wheel, showing the mechanism of the latter exposed; with the parts in the position occupied when combing. Figs. 9 and 10 are views similar to Fig. 8, but confined to the combing wheel. Fig. 9 shows the combing wheel tripped, and Fig. 10 shows the combing wheel lifted but about to lower. Figs. 11 and 12 show views similar to Figs. 9 and 10, but in diagrammatic form. Fig. 11 shows the combing wheel tripped or lifted and the top sheet moving forward. Fig. 12 shows the tail end of the top sheet as having just passed the plane of the combing wheel, with the latter down combing the next underlying sheet. Fig. 13 is a detail view showing the abutment member, the filling member and the rotatable member. Fig. 14 is a detail view of the releasable connections from the timed mechanism for lifting the combing wheel, with the parts of Fig. 13 shown in position, together with the gearing for breaking the connection. Fig. 15 is a detail view of the gears shown in Fig. 14, together with the members for supporting the same, looking in the direction of the arrow 26 in Fig. 14. Fig. 16 is a detail view of the filling member shown in Figs. 13 and 14.

Similar characters of reference indicate corresponding parts in the several views.

1 indicates a feed board or other suitable member constituting a sheet path or support, arranged adjacent to a printing or other machine. Suitable sheet forwarding or feeding means here taking the form of

positively driven rollers 3 and drop rollers 4 are provided to advance the sheet over said feed board.

Adjacent to the rear end of the feed board 1 is another sheet support 9, which may be either in the form of a pile elevating mechanism or, as here disclosed, in the form of a table preferably having a bank feeding device. The feed board 1 and the sheet support 9 may constitute one member, if desired. Intermediate the members 1 and 9 is a transfer or sheet feeding off device 10, for feeding the sheet forwardly from the member 9 to the member 1. Above the pile or bank and the sheet support are one or more sheet combing devices 11, in the present instance two, and since they are constructed alike, only one will be described.

12 is a combing wheel adapted to be raised and lowered by means of an eccentric. As here shown the eccentric 13 is loosely carried on a shaft 14 and directly mounts the combing wheel 12. The said combing wheel 12 is given, in the present instance, a continuous rotating motion from the shaft 14, irrespective of the up or down position of said wheel, by means of a pin and slot connection, such as the spider 15 fast on the shaft 14 and the pins 16 carried by the combing wheel (Fig. 7). So far as certain features of the invention are concerned, it is immaterial whether the combing wheel is employed to comb the sheets forwardly and rearwardly. In the present case the organization of the machine is such that the combing wheel rotates in a rearward direction. The shaft 14 is hung in a bracket or frame 17 carried by two pairs of arms 18, one of which arms constitutes a gear casing supporting the gears 19 which transmit motion from the shaft 20 to the shaft 14. The two pairs of arms 18 are arranged one above the other. The lower arms 18 are loosely supported on the shaft 20, while the upper arms 18 are supported on a pivot 20^a so as to move in parallelism.

21 is a stationary rack on the framework into which the pawl 22 drops when the combing wheel is lifted so as to prevent the arms 18 of the frame from turning around the shaft 20 and pivot 20^a. By the foregoing means, it will be observed, that only the combing wheel proper is lifted and lowered, and that the weight of the frame including the arms 18 is sustained by the rack 21.

Any suitable means may be employed for shifting the eccentric bushing 13, but the particular means here employed involve in themselves new and valuable features capable of use independently of the eccentric bushing 13.

22^a is a spring connected at one end to the stationary framing and at its other end to

75

130

a link 23 which is secured to the eccentric 13. This spring constantly urges the eccentric 13 in one direction, viz: in a direction to lift the combing device. This spring 5 may be considered as a lifting actuator or as an auxiliary actuating device for lifting the 10 combing wheel. Means are provided for normally restraining the action of this spring, which means may be, and in the present instance are, a timed mechanism. The said timed mechanism may act to shift the eccentric bushing in both directions to raise and lower the combing wheel in timed 15 relation with the other moving parts of the machine, or it may act merely to lower the combing wheel in timed relation, leaving the work of raising the combing wheel to the spring 22^a, the action of which latter it restrains until the sheet has been combed rear- 20 wardly a sufficient distance. The said timed mechanism may take many forms, but in the present instance a controller 24 is employed connected at one end to the arms 25 of the eccentric bushing 13 (Fig. 15) and receiving 25 its motion from the rockshaft 26 by means of the arm 27, rod 28 and rocker arm 29, the latter of which is pivoted at 30 on the combing wheel frame and connected to the controller 24 at the point 31. The periodic 30 rocking of the rockshaft 26 will thus raise and lower the combing wheel in timed relation with the other parts of the machine, and will restrain the action of the spring 22^a. The rockshaft 26 is mounted above the 35 rotating shaft 20, and may be rocked in any suitable manner. In the form here shown it receives its motion from the cam 32 (Fig. 8) pivoted lever 33 having cam roll 34, link 35, pivoted arms 36 (Figs. 2, 5 and 8) lifter bar 40 37 and upright link 38 having roll 39 resting on lifter bar 37. 38 is carried by two arms, one 40 being pivoted loosely on the rotating shaft 20 and the other 41 being secured to the rockshaft 26.

45 Suitable means are provided for breaking the connection between the eccentric bushing 13 and the timed actuating mechanism. In the present instance the controller 24 is composed of two telescoping members, one a 50 casing 42 and the other a sliding member 43, sliding in said casing. These two members are connected by means of two locking members 44 and 45 in the form of hooks which constitute a releasable connection between 55 the eccentric bushing 13 and the timed actuating mechanism. The means for breaking this connection may vary, but preferably there is a stationary abutment member 46, and a movable filling member 47, which 60 when brought together constitute a fulcrum against which a rotating member 48 acts to disengage the hooks 45 and 44 (Figs. 13, 14, 15 and 16). Mounted on the shaft 14 is a gear 49 engaging with a gear 50 carried on 65 a stud 51 in the arms 25 of the eccentric bushing. Meshing with the gear 50 is a gear 52 mounted on a stud 53 on the sliding member 43. On this same stud 53 is mounted the hook 45. The gear 52 drives the gear 48, which latter is mounted on the hook 45. 70 It will be understood that when the filling member 47 is brought into the plane of the teeth of gear 48, that the latter will draw said member 47 against the abutment 46. The continued rotation of gear 48 will then 75 cause the hook 45 to turn around its pivot 53 thereby disengaging the hooks 44 and 45. This will release the eccentric 13 from the restraining influence of the timed mechanism, and will permit the spring 22^a to assert its power causing the eccentric to be shifted quickly at a speed greater than the speed of the timed mechanism and causing the sliding member 43 to slide in the casing 80 42. The combing wheel will thus be lifted 85 quickly. At the same time the cam surface 54 on the sliding member 43 will pass beyond the point where the sliding rod 55 connected to pawl 22, is located, thereby permitting the spring 56 to turn the pawl 22 90 on its pivot 57 to engage the rack 21 (Figs. 11 and 12). The casing 42 under the influence of the timed mechanism now descends until the hooks 44 and 45 interlock, the spring 58 restoring them to their inter- 95 locked position. As the casing 43 and sliding member 44 now ascend, the eccentric bushing 13 will be turned to lower the combing wheel into contact with the pile or bank. As the said member 43 ascends, the cam face 100 54 will engage the rod 55 and disengage the pawl 22 from the rack 21.

The means for bringing the filling member 47 into the path of the rotating member 48 will vary, but as herein shown they consist of a sheet controlled trigger 59 suspended in the path of the sheets; preferably immediately in rear of the combing wheel and in the same plane longitudinally of the machine. In detail, a bracket 60 is provided 105 suitably secured to the combing wheel frame. Carried by this bracket are upper and lower guides 61 forming a throat into which the sheets are combed. Carried by the support for bracket 60 is a support 62 through which 115 slides a rod 63. Adjustably mounted on this rod 63 is the trigger 59. Adjustably mounted on this rod 63 are further the stops 64. The rod 63 is connected to a two armed lever 65 mounted at 66 on the comb- 120 ing wheel frame. The lever 65 is connected to the pivoted member 67 by means of the slotted link 68. The member 67 carries the filling member 47. The member 67 is pivoted on the loose bracket 69, which latter is 125 pivoted on the combing wheel frame at 70. A pull spring 71 normally holds the loose bracket 69 against the stop 72 so that in case the filling member 47 should hit the top of a tooth on 48, the spring 71 will give, and 130

hence the loose bracket 69, will yield in an upward direction.

73 is a spring for normally holding the filling member 47 out of the path of the rotating member 48.

As the sheet is combed into the throat 61 it will eventually engage the trigger 59, thereby causing a movement of the sliding rod 63 through the support 62. This movement will be transmitted through the connections described to the filling member 47 which will thereby be brought within reach of the rotating member 48, and is thereafter carried, by the latter, into engagement with the abutment member 46. The trigger 59 also serves to register the tail end of the sheet, and the stop 64 and the said trigger 59 can be so adjusted that the said stop 64 will not come in contact with the support 62 until some time after the combing wheel is tripped. The sheet will therefore continue to move, a short period after the combing wheel is tripped owing to its inertia, and when the stop 64 reaches the support 62 the sheet will be registered against the trigger 59. In this connection it is observed that, when the combing wheel lifts, the turning movement of the eccentric is in the same direction as the direction of rotation 30 of the combing wheel. Each combing wheel is tripped independently of the other, but both are raised and lowered simultaneously by the timed mechanism.

The shafts 20 and 26, as well as the entire combing wheel mechanism, are supported in a carriage 74 (Fig. 5) which is provided with bushings 75 adapted to slide on the longitudinal frame rods 76. These frame rods 76 are provided with racks 77 adapted to be engaged by the pinions 78 on the shaft 79 carried by the carriage 74. By rotating the knurled head 80 on shaft 79, the carriage 74, and with it the entire combing mechanism can be adjusted. The shaft 20 is rotated by means of the bevel gears 81 and 82, the former of which is carried by the shaft 20, and the other of which is mounted slidably on the shaft 83, supported in the framework, by means of a key 84.

In order to vary the amount of pressure with which the combing wheel engages the pile or bank of sheets, one of the lower arms 18 is provided with an extension 85 (Fig. 8) to which is secured a spring 86 carried by the rod 87 adjustable in the lug 88 by means of the nut 89. In the present instance where the combing wheel moves the sheet rearwardly, suitable means are provided for moving the sheet forwardly off the support 9, after the sheet has been combed rearwardly. Various means may be employed, but preferably two continuously rotating drawing-off rollers 90 are mounted above the sheet support 9, near the forward end 65 thereof. Sheet lifting fingers 91 are fur-

ther provided to raise the leading end of the sheet into engagement therewith. The fingers 91 are, in the present instance, pivoted on the lever 92 carried by the rock-shaft 93, which latter receives its motion from the cam 94 through the arm 95 and cam roller 96. The fingers 91 carry a cam 97 adapted to engage with the rod 98. As the lever 92 rocks, the fingers 91 slide back and forth over the leading end of the sheets. Upon the stroke in one direction, the fingers 91 pass beyond the leading end of the top sheet, and as they return they pass in under the said top sheet until the cam 97 engages the pin 98 when the fingers lift the sheet up against the rollers 90, (Fig. 11) thereby causing the sheet to be fed off the pile and into the bite of the rollers 99, from whence it is conveyed over the guides 100 to the sheet forwarding devices 3 and 4. A spring 101 holds the cam roll 96 against the cam 94.

In Fig. 8 the parts are shown in the position occupied when the sheet is being combed rearwardly. The combing action continues until the sheet engages the trigger 59 when the filling member 47 is brought against the abutment member 46 which causes the hooks 44 and 45 to become disengaged so as to permit the spring 22 to turn the eccentric bushing to lift the combing wheel. The parts now are in the position shown in Fig. 9. If the sheet does not engage the trigger 59 early enough, the timed mechanism will eventually turn the eccentric bushing to lift the combing wheel, without breaking the connection 44-45. The lifter fingers 91 will now move in under the sheet and lift it into engagement with the rollers 90, the combing wheel remaining in its elevated position. (See Fig. 11). If the trigger 59 was operated the timed mechanism 24 and the spring 58 will meanwhile have restored the broken connection 44-45, and will begin to lower the combing wheel (see Fig. 10). As soon as the tail end of the sheet has passed the vertical plane in which the combing wheel moves (Fig. 12) the combing wheel will come in contact with the pile or bank of sheets, and engage the next underlying sheet while the top sheet is being removed. The bank or pile of sheets may be pushed forward by hand or may be on an elevating table as previously described. In the present instance, however, the bank is fed forwardly intermittently by the following means.

Located at opposite ends of the support 9 are pulleys 102, 103 (Figs. 5 and 8) over which pass the tapes 104 or other sheet feeding means. The pulley 102 is mounted on the shaft 105 provided with the ratchet 106. Engaging with this ratchet 106 is a pawl 107 mounted on the lever 108, which lever 108 is mounted loosely on the shaft 105. At its 130

free end the lever 108 is provided with a cam roll 109 engaging the cam 110. Carried by the lever 108 is an extension 111 provided with a lug 112. A sheet tripper 113 is located adjacent to the leading edge 5 of the sheets and is provided with a hook 114 adapted to engage with the lug 112. The tripper is loosely mounted on the shaft 93 and is provided with a counterweight 115 10 normally tending to move the tripper 113 toward the sheets and the hook 114 off the lug 112. When the said hook 114 is off the lug 112 the lever 108 will be free to follow the cam 110 and the tapes 104 will be 15 moved forwardly. When the sheets have thus been moved forwardly the tripper 113 will be swung over until the hook 114 engages the lug 112. This will hold the extension 111 and will prevent the lever 108 from 20 following the cam 110 and therefore the movement of the tapes 104 will cease.

In the present case power is applied to cross shaft 189. This shaft is provided with a gear 190 meshing with gear 191 loose on 25 the cam shaft 192. Mounted fast on the cam shaft 192 is another gear 193. A suitable clutch mechanism, which need not be described, is interposed between the gear 191 and the cam shaft 192. Meshing with the 30 gear 193 is a gear 194, which transmits motion to shaft 83 (Figs. 1, 2, 3 and 4) by means of gears 195, 196, 197, 198 and 199. The shaft 83, as has been previously explained, drives the combing wheel. The 35 gears 195 and 196 are mounted on a shaft 200 which extends across the machine and carries the rollers 99 (Figs. 1 and 8) and carries at its other end a gear 201 (Figs. 1 and 3) meshing with a gear 202 mounted 40 eccentrically on the rocking lever 203 and which meshes with the gear 204 on the shaft 205 carrying the rollers 90. By this means a variable motion is imparted to the rollers 90 so that the sheet will be started slowly 45 and its speed gradually accelerated. The cam shaft 192 carries the cams 32, 94 and 110 for raising and lowering the combing wheel, for intermittently advancing the bank of paper and for actuating the lifter 50 fingers 91. The gear 194 (Figs. 1 and 4) further meshes with a pinion 206 which drives a gear 207 on the shaft 208. The shaft 208 carries one set of rollers 3 and drives a longitudinal shaft 209 by means 55 of bevel gears 210, and cross shafts 211 extend at intervals carrying other rollers 3, said cross shafts being driven by means of bevel gears 212.

What is claimed, is:

- 60 1. The combination with a sheet support and a sheet feeding device arranged to operate on the sheets on said support, and adapted to be raised and lowered with respect thereto, a lifting actuator exerting a constant lifting force upon the sheet feeding

device, timed mechanism normally controlling the raising of the sheet feeding device, arranged to lower the sheet feeding device at predetermined intervals and having connection with the lifting actuator to normally restrain the action of such lifting actuator, and a sheet controlled device arranged when actuated by a sheet to release the connection between the timed mechanism and lifting actuator to permit the lifting actuator to become operative independent of the control normally exercised by the timed mechanism. 70 75

2. The combination with a sheet support and a sheet feeding device arranged to operate on the sheets on said support and adapted to be raised and lowered with respect thereto, timed mechanism normally controlling the sheet feeding device to cause the same to be alternately raised and lowered at 80 definite intervals, a lifting actuator exerting a continuous lifting force upon the sheet feeding device, connections between the timed mechanism and lifting actuator whereby the action of the lifting actuator 85 will be normally restrained and controlled by the timed mechanism, and a sheet controlled device in said connections arranged when actuated to release the lifting actuator thereby permitting the same to become operative to lift the sheet feeding means at a time earlier than the definite interval between raising and lowering normally controlled by the timed mechanism. 90 95

3. The combination with a sheet support and a sheet feeding device arranged to operate on the sheets on said support, and adapted to be raised and lowered with respect thereto, timed mechanism arranged to normally control the lifting and lowering of the sheet feeding device at certain regular intervals, a lifting actuator exerting a force to raise the sheet feeding device at a time prior to the time of lifting controlled by the timed mechanism, a releasable connection between the timed mechanism and the lifting actuator whereby the action of the lifting actuator will be normally restrained by the timed mechanism, and a sheet-controlled device arranged when actuated by a sheet to release the connection between the timed mechanism and lifting actuator to permit the lifting actuator to become operative to lift the sheet feeding device prior to the time of lifting controlled by the timed mechanism. 100 105 110 115 120

4. The combination with a sheet support and a sheet feeding device arranged to operate on the sheets on said support, and adapted to be raised and lowered with respect thereto, relatively slow-acting timed mechanism arranged to normally control the lifting and lowering of the sheet feeding device at certain regular intervals, a relatively quick-acting lifting actuator exerting a 125 130

- force to lift the sheet feeding device in advance of the time of lifting normally controlled by the timed mechanism, a releasable connection between the timed mechanism and the lifting actuator whereby the action of the lifting actuator will be normally restrained by the timed mechanism, and a sheet-controlled device arranged when actuated to release the connection aforesaid
- 10 to thereby permit the relatively quick-acting lifting actuator to lift the sheet feeding device in advance of the relatively slow lifting movement controlled by the timed mechanism.
- 15 5. The combination with a sheet support and a sheet feeding device arranged to operate on the sheets on said support, and adapted to be raised and lowered with respect thereto, timed mechanism arranged to normally control the lifting and lowering of the sheet feeding device at certain regular intervals, a lifting actuator exerting a force to raise the sheet feeding device at a time prior to the time of lifting controlled by the
- 20 25 timed mechanism, a releasable connection between the timed mechanism and the lifting actuator whereby the action of the lifting actuator will be normally restrained by the timed mechanism, a sheet-controlled device arranged when actuated by a sheet to release the connection between the timed mechanism and lifting actuator to permit the lifting actuator to become operative to lift the sheet feeding device prior to the
- 30 35 time of lifting controlled by the timed mechanism, and means for restoring the connection between the timed mechanism and lifting actuator after the lifting actuator has raised the sheet feeding device.
- 40 6. The combination with a sheet support and a rotating combing wheel arranged to operate on the sheets upon said support, and adapted to be raised and lowered with respect thereto, a lifting actuator exerting a
- 45 50 constant lifting force upon the combing wheel, timed mechanism normally controlling the raising of the combing wheel, arranged to lower the combing wheel at predetermined intervals and having connection with the lifting actuator to normally restrain the action of such lifting actuator, a sheet-controlled device arranged when actuated by a sheet to release the connection between the timed mechanism and lifting actuator to permit the lifting actuator to become operative to lift the combing wheel prior to the time of lifting normally controlled by the timed mechanism, and means for restoring the connection between the
- 55 60 timed mechanism and lifting actuator after the lifting actuator has operated to raise the combing wheel.
7. In a sheet feeding machine, a sheet support, a combing device arranged to operate upon the sheets thereon, and means for rais-

ing and lowering the combing device with respect to the sheet support comprising, an eccentric member arranged when operated to cause the actual raising and lowering of the combing device, a timed mechanism controlling the movements of the eccentric member in raising and lowering the combing device, connections between the timed mechanism and the eccentric member, an auxiliary actuating device constantly urging the eccentric member in one direction at a speed greater than that of the timed mechanism and normally restrained by said timed mechanism, means controlled by the advance of a sheet for breaking the connection between the timed mechanism and the eccentric member to thereby permit the auxiliary actuating device to impart a quick shifting movement to the eccentric member, and means for restoring the broken connection aforesaid.

8. In a sheet feeding machine, a sheet support, a combing device arranged to operate upon the sheets on said support, and means for raising and lowering the combing device comprising, an eccentric bushing mounting the combing device, timed mechanism controlling the movement of the eccentric bushing in opposite directions, connections between the timed mechanism and the eccentric bushing, an auxiliary actuating device constantly urging the eccentric bushing in one direction at a speed greater than that of the timed mechanism and normally restrained by the latter, means controlled by the advance of a sheet for breaking the connection between the timed mechanism and the eccentric bushing to thereby permit said auxiliary actuating device to quickly shift the eccentric bushing, and means for restoring the broken connection between the timed mechanism and the eccentric bushing.

9. In combination with a sheet support and a combing device arranged to operate upon the sheets on said support, and adapted to be raised and lowered with respect thereto, timed mechanism arranged to lower the combing device at predetermined intervals and arranged further to normally permit the combing device to be raised at predetermined times, a lifting actuator normally connected with the timed mechanism and acting normally to raise the combing device only so fast as permitted to do so by the timed mechanism, and means controlled by the advance of the sheet to break the connection between the lifting actuator and timed mechanism to permit the lifting actuator to operate independently of the timed mechanism.

10. In combination with a sheet support and a combing device arranged to operate upon the sheets on said support, and adapted to be raised and lowered with respect thereto, timed mechanism arranged to lower the

- combing device at predetermined intervals and arranged further to normally permit the combing device to be raised at predetermined times, a lifting actuator normally connected with the timed mechanism and acting normally to raise the combing device only so fast as permitted to do so by the timed mechanism, means controlled by the advance of the sheet to break the connection between the lifting actuator and timed mechanism to permit the lifting actuator and timed mechanism to permit the lifting actuator to operate independently of the timed mechanism, and means for restoring the broken connection between the timed mechanism and the lifting actuator after the lifting actuator has raised the combing device.
11. In a sheet feeding machine, the combination with a sheet support, of a combing wheel, an eccentric support on which the combing wheel is mounted, means for rotating the combing wheel, a lifting actuator exerting a constant force on the eccentric support to turn the same to lift the combing wheel, timed mechanism normally connected with the eccentric support arranged when so connected to control the movements of the eccentric support to raise and lower the combing wheel at regular intervals, a sheet controlled device arranged when actuated by a sheet to disconnect the timed mechanism from the eccentric support to thereby permit the lifting actuator to turn the eccentric support to lift the combing wheel independent of control of the timed mechanism, and means for restoring the connection between the eccentric support and the timed mechanism after the combing wheel has been raised by the lifting actuator.
12. In combination, a sheet support, a combing wheel, an eccentric support on which the combing wheel is mounted, timed mechanism normally connected with the eccentric support arranged when so connected to positively move the eccentric support to lower the combing wheel at definite intervals, a lifting actuator exerting a constant force to turn the eccentric support to lift the combing wheel as fast as permitted by the timed mechanism, a sheet controlled device arranged when actuated by the sheet to disconnect the timed mechanism from the eccentric support to thereby render the lifting actuator free to turn the eccentric support independent of control of the timed mechanism, and means for restoring the connection between the timed mechanism and the eccentric support after the combing wheel has been raised by the lifting actuator so that upon the next movement the timed mechanism will positively turn the eccentric support to again lower the combing wheel.
13. In a sheet feeding machine, a sheet support, a combing wheel frame loosely mounted on a member at one end, a combing wheel mounted in the free end of the frame, means for driving said combing wheel, and means for raising and lowering the combing wheel in the frame.
14. In a sheet feeding machine, a sheet support, a combing wheel frame pivoted on a member at one end, a combing wheel mounted in the free end of the frame, means for driving said combing wheel, and means for raising and lowering the combing wheel in the frame independently of the pivotal movement of the frame on the member carrying the same.
15. In a sheet feeding machine, a sheet support, a shaft, a combing wheel frame mounted loosely on the shaft, a combing wheel mounted in the free end of the frame, driving connections from the shaft to the combing wheel, and means for raising and lowering the combing wheel in the frame.
16. In a sheet feeding machine, a sheet support, a frame pivoted on the framework, a shaft mounted in the free end of the frame, means for rotating the shaft, an eccentric bushing on said shaft, a combing wheel carried thereby, means for shifting the eccentric bushing to raise and lower the combing wheel, and means for rotating the combing wheel from the shaft irrespective of the position of the eccentric bushing.
17. In a sheet feeding machine, a sheet support, a frame pivoted on the framework, a shaft mounted in the free end of the frame, means for rotating the shaft, an eccentric bushing on said shaft, a combing wheel carried thereby, means for shifting the eccentric bushing to raise and lower the combing wheel, and a pin and slot connection between the shaft and the combing wheel.
18. In a sheet feeding machine, a sheet support, a combing device arranged to operate upon the sheets on said support, a supporting frame for the combing device freely movable to permit the combing device to properly engage the sheets on the support, and means for tripping the combing device with respect to the sheet support comprising, means for temporarily supporting the combing frame, and means for raising the combing device while the combing frame is so supported.
19. In a sheet feeding machine, a sheet support, a combing wheel normally resting upon the sheets on said support, a supporting frame for the combing wheel freely movable to permit the combing wheel to rest upon the sheets on the support, means for raising the combing wheel with respect to the sheet support, and means for temporarily supporting the combing frame while the combing wheel is being lifted.
20. In a sheet feeding machine, a sheet support, a combing wheel normally resting upon the sheets on said support, a frame in

which the combing wheel is mounted, said frame being loosely mounted to adapt itself to the height of the sheets, sheet-controlled mechanism for raising the combing wheel in the frame, and means for temporarily supporting the frame while the combing wheel is being raised.

21. In combination with a sheet support, a combing frame mounted to swing about a center of support, a combing wheel mounted in said frame arranged when in engagement with the sheets on the sheet support to support the free end of the combing frame, and sheet-controlled mechanism for simultaneously supporting the free end of the combing frame and raising the combing wheel within the frame.

22. In combination with a sheet support, a combing frame pivotally supported at one end with its free end overhanging the sheet support, a combing wheel journaled in the free end of the combing frame arranged when in engagement with the sheets on the support to sustain the free end of the combing frame, sheet-controlled mechanism for raising the combing wheel in the frame, and a temporary support for the free end of the combing frame rendered operative upon the actuation of the combing wheel raising mechanism.

23. In a sheet feeding machine, a sheet support, a combing frame pivotally supported at one end with its free end overhanging the sheet support, an eccentric bushing mounted in the free end of the combing frame, a combing wheel journaled on said bushing serving when in engagement with the sheets to support the free end of the combing frame, means for turning the eccentric bushing to raise the combing wheel, and means for temporarily supporting the combing frame when the eccentric bushing is turned to raise the combing wheel.

24. In a sheet feeding machine, a sheet support, combing frame pivotally supported at one end with its free end overhanging the sheet support, an eccentric bushing mounted in the free end of the combing frame, a combing wheel journaled on said bushing serving when in engagement with the sheets to support the free end of the combing frame, a lifting actuator constantly acting on the eccentric bushing to turn the same to raise the combing wheel, means normally restraining said lifting actuator, a sheet controlled trip for releasing the restraining means, and means for temporarily supporting the free end of the combing frame when the eccentric bushing is turned to raise the combing wheel.

25. In a sheet feeding machine, a sheet support, a combing wheel arranged to operate upon the sheets on said support, a combing frame for the combing wheel

mounted to adjust itself to the height of the sheets, sheet controlled mechanism for raising the combing wheel within the frame, means for temporarily supporting the combing frame when the combing wheel is raised, and means for again lowering the combing wheel into engagement with the sheets and freeing the combing frame of the temporary support.

26. In a sheet feeding machine, a sheet support, a combing frame pivoted at one end with its free end overhanging the sheet support, an eccentric bushing mounted in the free end of the combing frame, a combing wheel carried by the eccentric bushing, sheet-controlled mechanism for turning the eccentric bushing to raise the combing wheel, means for supporting the free end of the combing frame when the combing wheel is raised, means for turning the eccentric bushing to lower the combing wheel, and means for releasing the temporary support for the combing frame when the combing wheel is lowered.

27. In a sheet feeding machine, a sheet support, a combing frame pivotally supported at one end and having its free end overhanging the sheet support, an eccentric bushing journaled in the free end of the combing frame, a combing wheel supported by the eccentric bushing, a lifting actuator constantly acting on the eccentric bushing to turn the same to lift the combing wheel, means normally restraining the lifting actuator, a sheet-controlled trip for releasing the restraining means to permit the lifting actuator to become operative to raise the combing wheel, means for temporarily supporting the free end of the combing frame when the combing wheel is raised, means for turning the eccentric bushing to lower the combing wheel, and means for simultaneously releasing the temporary support.

28. In a sheet feeding machine, a sheet support, a combing frame movably mounted above the sheet support, an eccentric bushing journaled in the combing frame, a combing wheel supported by the eccentric bushing arranged when in engagement with the sheets to support the combing frame, a lifting actuator constantly acting on the eccentric bushing to turn the same to raise the combing wheel, timed mechanism normally connected with the eccentric bushing to control the raising and lowering of the combing wheel at regular intervals, sheet-controlled mechanism for releasing the connections between the timed mechanism and the eccentric bushing to permit the lifting actuator to become operative to raise the combing wheel, and means for temporarily supporting the combing frame when the combing wheel has been raised.

29. In a sheet feeding machine, a sheet support, a combing wheel frame movably

- mounted above the sheet support, an eccentric bushing journaled in the combing wheel frame, a combing wheel supported by the eccentric bushing arranged when in engagement with the sheets to support the combing wheel frame, timed mechanism normally connected with the eccentric bushing having a movement in one direction to turn the eccentric bushing to lower the combing wheel and having a movement in the opposite direction to allow the eccentric bushing to be turned to raise the combing wheel, a lifting actuator constantly acting on the eccentric bushing to turn the same to raise the combing wheel as fast as permitted by the timed mechanism, sheet controlled mechanism for releasing the connection between the timed mechanism and the eccentric bushing to permit the lifting actuator to become operative to raise the combing wheel irrespective of the timed mechanism, means for temporarily supporting the combing frame when the eccentric bushing has been turned to raise the combing wheel, and means for releasing the said temporary support when the timed mechanism has turned the eccentric bushing to lower the combing wheel.
30. A sheet support, a combing device, means for imparting a feeding motion to the combing device, an eccentric bushing for raising and lowering the combing device with respect to the sheet support, and means for shifting the eccentric bushing intermittently.
31. A sheet support, a combing device, means for imparting a feeding motion to the combing device, an eccentric bushing for raising and lowering the combing device with respect to the sheet support, and means for rocking the eccentric bushing intermittently.
32. A sheet support, a rotary combing device, means for imparting a rotary feeding motion to the combing device, an eccentric bushing for raising and lowering the combing device with respect to the sheet support, and means for shifting the eccentric bushing intermittently.
33. A sheet support, a rotary combing device, means for imparting a rotary feeding motion to the combing device, an eccentric bushing for raising and lowering the combing device with respect to the sheet support, and means for rocking the eccentric bushing intermittently.
34. A sheet support, a combing device, means for imparting a feeding motion to the combing device, an eccentric bushing for raising and lowering the combing device with respect to the sheet support, means for shifting the eccentric bushing intermittently, and means actuated by the movement of the sheet for controlling the shifting means.
35. A sheet support, a combing device, means for imparting a feeding motion to the combing device, an eccentric bushing for raising and lowering the combing device with respect to the sheet support, means for shifting the eccentric bushing intermittently, and means actuated by the movement of the sheet for controlling the shifting means.
- means for imparting a feeding motion to the combing device, an eccentric bushing for raising and lowering the combing device with respect to the sheet support, means for shifting the eccentric bushing intermittently, and means actuated by the movement of the sheet for controlling the shifting means.
36. A sheet support, a rotary combing device, means for imparting a rotary feeding motion to the combing device, an eccentric bushing for raising and lowering the combing device with respect to the sheet support, means for shifting the eccentric bushing intermittently, and means actuated by the movement of the sheet for controlling the shifting means.
37. A sheet support, a rotary combing device, means for imparting a rotary feeding motion to the combing device, an eccentric bushing for raising and lowering the combing device with respect to the sheet support, means for rocking the eccentric bushing intermittently, and means actuated by the movement of the sheet for controlling the rocking means.
38. A sheet support, a combing device, means for imparting a feeding motion to the combing device, an eccentric bushing for raising and lowering the combing device with respect to the sheet support, means under the control of the sheet for automatically shifting the eccentric bushing to raise the combing device, and means for automatically shifting the eccentric bushing to restore the combing device to its lowermost position.
39. A sheet support, a combing device, means for imparting a feeding motion to the combing device, an eccentric bushing for raising and lowering the combing device with respect to the sheet support, means under the control of the sheet for automatically shifting the eccentric bushing in one direction to raise the combing device, and means for automatically shifting the eccentric bushing in the opposite direction to restore the combing device to its lowermost position.
40. A sheet support, a rotary combing device, means for imparting a rotary feeding motion to the combing device, an eccentric bushing for raising and lowering the combing device with respect to the sheet support, means under the control of the sheet for automatically shifting the eccentric bushing to raise the combing device, and means for automatically shifting the eccentric bushing to restore the combing device to its lowermost position.
41. A sheet support, a rotary combing device, means for imparting a rotary feeding motion to the combing device, an eccentric bushing for raising and lowering the combing device with respect to the sheet support, means under the control of the sheet for automatically shifting the eccentric bushing to raise the combing device, and means for automatically shifting the eccentric bushing to restore the combing device to its lowermost position.

tomatically shifting the eccentric bushing in one direction to raise the combing device, and means for automatically shifting the eccentric bushing in the opposite direction 5 to restore the combing device to its lowermost position.

42. In a sheet feeding machine, a sheet support, a combing device, means for imparting a feeding motion to the combing device, an eccentric bushing mounting the 10 combing device, and means for shifting the eccentric bushing to raise and lower the combing device with respect to the sheet support.

15 43. In a sheet feeding machine, a sheet support, a combing wheel, an eccentric bushing mounting the combing wheel, means for imparting a rotating feeding motion to the combing wheel, and means for shifting the 20 eccentric bushing to raise and lower the combing wheel with respect to the sheet support.

25 44. In a sheet feeding machine, a sheet support, a combing wheel, an eccentric bushing mounting the combing wheel, means for imparting a continuous rotating feeding motion to the combing wheel, and means for intermittently shifting the eccentric bushing to raise and lower the combing wheel with 30 respect to the sheet support.

35 45. In a sheet feeding machine, a sheet support, a combing wheel, means for imparting a continuous rotary feeding motion to the combing wheel, an eccentric bushing mounting the combing wheel, and means for intermittently rocking the eccentric bushing to raise and lower the combing wheel with 40 respect to the sheet support.

45 46. In a sheet feeding machine, a sheet support, a combing device, means for imparting a feeding motion to the combing device, an eccentric bushing mounting the combing device, means for shifting the eccentric bushing intermittently to raise and 50 lower the combing device with respect to the sheet support, and means actuated by the movement of the sheet for controlling the shifting means.

55 47. In a sheet feeding machine, a sheet support, a combing wheel, an eccentric bushing mounting the combing wheel, means for imparting a continuous rotary feeding motion to the combing wheel, means for shifting the eccentric bushing intermittently to raise and lower the combing wheel with respect to the sheet support, and means actuated by the movement of the sheet for controlling the shifting means.

60 48. In a sheet feeding machine, a sheet support, a combing wheel, means for imparting a continuous rotary feeding motion to the combing wheel, an eccentric bushing mounting the combing wheel, means for rocking the eccentric bushing intermittently 65 to raise and lower the combing wheel with

respect to the sheet support, and means actuated by the movement of the sheet for controlling the rocking means.

49. In a sheet feeding machine, a sheet support, a combing device, means for imparting a feeding motion to the combing device, an eccentric bushing mounting the combing device, means under the control of the sheet for automatically shifting the eccentric bushing to raise the combing device, 75 means for automatically shifting the eccentric bushing to restore the combing device to its lowermost position.

50. In a sheet feeding machine, a sheet support, a combing wheel, means for imparting a continuous rotary feeding motion to the combing wheel, an eccentric bushing mounting the combing wheel, means under the control of the sheet for automatically shifting the eccentric bushing to raise the 80 combing wheel, and means for automatically shifting the eccentric bushing to restore the combing wheel to its lowermost position.

51. In a sheet feeding machine, a sheet support, a combing wheel, means for rotating the combing wheel, an eccentric bushing mounting the combing wheel, means under the control of the sheet for automatically shifting the eccentric bushing in one direction to raise the combing wheel, and means 90 for automatically shifting the eccentric bushing in the opposite direction to restore the combing wheel to its lowermost position.

52. In a sheet feeding machine, a sheet support, a combing wheel, an eccentric bushing mounting the combing wheel, means for imparting a rotating feeding motion to the combing wheel, means under the control of the sheet for automatically rocking the eccentric bushing in one direction to raise the 100 combing wheel, and means for automatically rocking the eccentric bushing in the opposite direction to restore the combing wheel to its lowermost position.

53. In a sheet feeding machine, a sheet support, a combing wheel, an eccentric bushing to raise and lower the combing wheel with respect to the sheet support, and means for rotating the combing wheel independently of the raising and lowering motion 110 imparted by the eccentric bushing.

54. In a sheet feeding machine, a sheet support, a combing wheel, an eccentric bushing mounting the combing wheel, means for intermittently rocking the eccentric bushing 120 to raise and lower the combing wheel with respect to the sheet support, and means for continuously rotating the combing wheel independently of the raising and lowering motion imparted by the eccentric bushing.

55. In a sheet feeding machine, a sheet support, a combing wheel, an eccentric bushing mounting the combing wheel, means under the control of the sheet for automatically shifting the eccentric bushing to raise 130

the combing wheel, means for automatically shifting the eccentric bushing to restore the combing wheel to its lowermost position, and means for rotating the combing wheel independently of the raising and lowering motion imparted by the eccentric bushing.

5 56. In a sheet feeding machine, a sheet support, a combing wheel, an eccentric bushing mounting the combing wheel, means under the control of the sheet for automatically 10 rocking the eccentric bushing in one direction to raise the combing wheel, means for automatically rocking the eccentric bushing in the opposite direction to restore the combing wheel to its lowermost position, and means for rotating the combing wheel independently of the raising and lowering motion imparted by the eccentric bushing.

15 57. In a sheet feeding machine, a sheet support, a combing device, an eccentric bushing mounting the combing device, means for imparting a feeding movement to the combing device, and means for shifting the eccentric bushing in the direction 20 of the feeding movement of the combing device.

25 58. In a sheet feeding machine, a sheet support, a combing wheel, means for imparting a rotary feeding movement to the combing wheel, an eccentric bushing mounting the combing wheel, and means for partially 30 rotating the eccentric bushing in the direction of rotation of the combing wheel.

35 59. In a sheet feeding machine, a sheet support, a combing wheel, means for imparting a continuous rotating feeding movement to the combing wheel, an eccentric bushing mounting the combing wheel, means for intermittently 40 rotating the eccentric bushing in the direction of the feeding movement of the combing wheel to raise the combing wheel with respect to the sheet support, and means for intermittently rotating the eccentric bushing in the opposite 45 direction to lower the combing wheel on the sheet support.

50 60. In a sheet feeding machine, a sheet support, a combing device, an eccentric member for raising and lowering the combing device, means for turning the eccentric member, a member connected to the turning means, a member connected to the eccentric member, a releasable connection between the 55 said two members, a fulcrum member, a rotating member connected with the releasable connection arranged to act against the fulcrum member to free the releasable connection aforesaid whereby the two members are disconnected, means for turning the eccentric bushing when the connection is thus 60 broken independently of the first turning means, and means for restoring the broken connection.

65 61. In a sheet feeding machine, a sheet support, a combing wheel, an eccentric mem-

ber for raising and lowering the combing wheel, means for turning the eccentric member, a member connected to the turning means, a second member connected to the eccentric member, a releasable connection 70 between the said two members, a fulcrum member, a rotating member connected with the releasable connection arranged to act against the fulcrum member to operate the releasable connection whereby the two members are disconnected, means for turning the eccentric member when the connection is thus broken between the two members independently of the first turning means, and means for restoring the broken connection.

75 62. In a sheet feeding machine, a sheet support, a combing wheel, an eccentric member for raising and lowering the combing wheel, means for turning the eccentric member, a member connected to the turning means, a second member connected to the eccentric member, a releasable connection 80 between the said two members, a fulcrum member, a rotating member carried by the releasable connection arranged to act against the fulcrum member to operate the releasable connection and thereby disconnect the two members aforesaid, means for turning the eccentric member to raise the 85 combing wheel when the connection between the two members is thus broken independently of the first turning means, and means for restoring the broken connection.

90 63. In a sheet feeding machine, a sheet support, a combing wheel, an eccentric member for raising and lowering the combing wheel, means for turning the eccentric member, a member connected to the turning means, a member connected to the eccentric member, a releasable connection between the 95 said two members, a lifting actuator constantly acting on the eccentric member to turn the same to raise the combing wheel, the turning means arranged when connected with the eccentric member to restrain the action of the lifting actuator in one direction and having a movement in the opposite direction to turn the eccentric member to lower the combing wheel, a fulcrum member, a rotating member connected with the releasable connection arranged to act against the fulcrum member to operate the releasable connection whereby the connection between the two members aforesaid 100 will be broken to permit the constantly acting lifting actuator to turn the eccentric member to raise the combing wheel independent of the restraint normally exercised by the turning means.

105 64. In a sheet feeding machine, a sheet support, a combing device, a shaft mounting said combing device, an eccentric bushing for raising and lower the combing device, means for turning the eccentric bush- 110

ing, a member connected to the turning means, a member pivotally connected to the eccentric bushing, a pivoted lever forming a connection between the two members, a rotating member on the pivoted lever, means for driving said rotary member from the shaft, a fulcrum against which said rotating member acts to turn the lever on its pivot whereby the connection between the two members is broken, means for turning the eccentric bushing when the connection is thus broken independently of the first turning means, and means for restoring the broken connection.

65. In a sheet feeding machine, a combing device, a shaft mounting said combing device, an eccentric bushing for raising and lowering the combing device, means for turning the eccentric bushing, a member connected to the turning means, a member pivotally connected to the eccentric bushing, a lever pivoted to the second member forming a releasable connection between the two members, a rotating member on the pivoted lever, means for driving said rotary member from the shaft, a fulcrum member against which said rotating member acts to turn the lever on its pivot whereby the connection between the two members is broken, means for turning the eccentric bushing when the connection is broken independently of the first turning means, and means for restoring the broken connection.

66. In a sheet feeding machine, a sheet support, a combing wheel, an eccentric bushing mounting the combing wheel for raising and lowering the same, a shaft for driving the combing wheel, means for turning the eccentric bushing, a reciprocating member connected to the turning means, a member pivotally connected to the eccentric bushing, a lever pivoted on the second member forming a releasable connection between the two members, a rotating member on the pivoted lever, means for driving said rotating member from the shaft, a fulcrum against which said rotating member acts to turn the lever on its pivot whereby the connection between the two members is broken, means for turning the eccentric bushing to raise the combing wheel when the connection is thus broken independently of the first turning means, and means for restoring the broken connection.

67. In a sheet feeding machine, a sheet support, a combing device, a shifting member for raising and lowering the combing device, power means for operating said shifting member, a member connected to the power means, a second member connected to the shifting member, a releasable connection between the said two members, a lifting actuator arranged to operate the shifting member to raise the combing device when the connection between the two members

aforesaid is broken, a rotating member connected with the releasable connection, a fulcrum against which the rotating member may act to operate the releasable connection, and means controlled by the advance of a sheet for positioning said fulcrum in the path of the rotating member.

68. In a sheet feeding machine, a sheet support, a combing device, an eccentric bushing mounting the combing device for raising and lowering the same, means for turning said eccentric bushing, a member connected to the turning means, a second member connected to the eccentric bushing, a releasable connection between the said two members, a lifting actuator arranged to turn the eccentric bushing to lift the combing wheel when the releasable connection has been operated to disconnect the two members aforesaid, a rotating member connected with the releasable connection, a fulcrum member against which the rotating member may act to operate the releasable connection, and means controlled by the advance of a sheet for positioning the fulcrum in the path of the rotating member.

69. In a sheet feeding machine, a sheet support, a combing wheel, an eccentric bushing mounting the combing wheel for raising and lowering the same with respect to the sheet support, means for turning the eccentric bushing, a member connected to the turning means, a second member connected to the eccentric bushing, a releasable connection between the said two members, a lifting actuator connected with the eccentric bushing and arranged to turn the same to raise the combing wheel when the connection between the two members aforesaid is broken, a rotating member connected with the releasable connection, a fulcrum against which the rotating member may act to operate the releasable connection, means controlled by the advance of a sheet for positioning the fulcrum in the path of the rotating member, and means for restoring the connection between the two members aforesaid.

70. In a sheet feeding machine, a sheet support, a combing device, an eccentric member for raising and lowering the combing device, means for turning the eccentric bushing, two members, one connected to the turning means and the other to the eccentric member, a pivoted lever forming a connection between the two members, a rotating member on said lever, a fulcrum against which said rotating member acts to turn the lever around its pivot whereby the connection between the two members is broken, means for turning the eccentric member when the connection is broken independently of the first turning means, and means for restoring the broken connection.

71. In a sheet feeding machine, a sheet

support, a combing device, an eccentric bushing for raising and lowering the combing device, means for turning the eccentric bushing, two members, one connected to the turning means and the other to the eccentric bushing, a pivoted lever forming a connection between the two members, a rotating member on said lever, a fulcrum against which said rotating member acts to turn the lever around its pivot whereby to break the connection between the two members, means for turning the eccentric bushing when the connection is broken, independently of the first turning means, and means for restoring the broken connection.

72. In a sheet feeding machine, a sheet support, a combing wheel, an eccentric bushing for raising and lowering the combing wheel, means for turning the eccentric bushing, two members, one connected to the turning means and the other to the eccentric bushing, a pivoted lever forming a connection between the two members, a rotating member on said lever, a fulcrum against which said rotating member acts to turn the lever around its pivot whereby to break the connection between the two members, a lifting actuator acting on the eccentric bushing to turn the same to raise the combing wheel when the connection is broken, and means for restoring the broken connection between the members aforesaid.

73. In a sheet feeding machine, a sheet support, a combing device, an eccentric bushing for raising and lowering the combing device, means for turning the eccentric bushing, two members, one connected to the turning means and the other to the eccentric bushing, a pivoted lever forming a connection between the two members, a rotating member on said lever, a fulcrum against which said rotating member may act to turn the lever around its pivot to release the connection between the two members, means controlled by the advance of the sheet for positioning the fulcrum in the path of the rotating member, means for turning the eccentric bushing to raise the combing wheel when the connection is thus released, and means for restoring the connection between the two members aforesaid.

74. In a sheet feeding machine, a sheet support, a combing device, shifting mechanism for raising and lowering the combing device, power means for operating the shifting mechanism, two members, one connected to the power means and the other to the shifting mechanism, a releasable connection between said two members, a rotating member connected with the releasable connection, a fulcrum against which the rotating member may act to operate the releasable connection to thereby disconnect the two members aforesaid, means for operating the shifting mechanism to raise the combing device when

the connection between the two members is thus broken, and means for restoring the broken connection.

75. In a sheet feeding machine, a sheet support, a combing device, shifting mechanism for raising and lowering the combing device, power means for operating the shifting mechanism, two members, one connected to the power means and the other to the shifting mechanism, a releasable connection between said two members, a rotating member connected with the releasable connection, a stationary abutment, a filling member, means controlled by the advance of a sheet for positioning the filling member in the path of the rotating member whereby the rotating member will carry the filling member into engagement with the stationary abutment to form a fulcrum against which the rotating member may act to operate the releasable connection, means for actuating the shifting mechanism to raise the combing device when the releasable connection has been operated to disconnect the two members aforesaid, and means for restoring the broken connection between the said two members.

76. In a sheet feeding machine, a sheet support, a combing device, an eccentric bushing for raising and lowering the combing device, means for turning the eccentric bushing, two members, one connected to the turning means and the other to the eccentric bushing, a releasable connection between the said two members, a stationary abutment, a rotating member connected with the releasable connection, a filling member, means controlled by the advance of a sheet for positioning the filling member in the path of the rotating member whereby the rotating member will carry the filling member into engagement with the stationary abutment to form a fulcrum against which the rotating member may act to operate the releasable connection and thereby disconnect the two members, means for turning the eccentric bushing when the connection is thus broken independently of the first turning means, and means for restoring the broken connection.

77. In a sheet feeding machine, a sheet support, a combing device, an eccentric bushing for raising and lowering the combing device, means for turning the eccentric bushing, two members, one connected to the turning means and the other to the eccentric bushing, a pivoted lever forming a releasable connection between the two members, a stationary abutment, a rotating member connected with the pivoted lever, a filling member, means controlled by the advance of a sheet for positioning the filling member in the path of the rotating member whereby the rotating member will carry the filling member into contact with the station-

- ary abutment to form a fulcrum against which the rotating member may act to swing the pivoted lever on its support to disconnect the two members aforesaid, means for turning the eccentric bushing when the connection between the two members is broken independently of the first turning means, and means for restoring the broken connection between the two members.
78. In a sheet feeding machine, a combing wheel, an eccentric bushing mounting the combing wheel for raising and lowering the same with respect to the sheet support, a shaft on which the combing wheel is driven, means for turning the eccentric bushing, two members, one connected to the turning means and the other to the eccentric bushing, a pivoted lever forming a releasable connection between the two members, a gear on the shaft, an intermeshing gear on the pivotal support, connecting the eccentric bushing and the second member aforesaid, an intermeshing gear on the pivotal support of the pivoted lever, a rotating member on the pivoted lever driven by the last-mentioned gear, a fulcrum against which the rotating member acts to turn the lever around its pivot whereby to break the connection between the two members aforesaid, means for turning the eccentric bushing to raise the combing wheel when the connection is thus broken, and means for restoring the broken connections.
79. In a sheet feeding machine, a sheet support, a combing wheel, an eccentric bushing mounting the combing wheel for raising and lowering the same with respect to the sheet support, a shaft for driving the combing wheel, means for turning the eccentric bushing, two members, one connected to the turning means and the other to the eccentric bushing, a releasable connection between the said two members, a rotating member carried by the releasable connection and driven from the shaft aforesaid, a fulcrum against which said rotating member acts to operate the releasable connection to disconnect the two members aforesaid, means for turning the eccentric bushing to raise the combing wheel when the connection between the two members is broken, and means for restoring the broken connection.
80. In a sheet feeding machine, the combination with a sheet support and a combing device, of means for raising and lowering the combing device comprising, an eccentric bushing, timed mechanism for turning said bushing, a member under the control of the timed mechanism, an extensible connection between the eccentric bushing and the member aforesaid, a disengageable connection between the extensible connection and the aforesaid member whereby the eccentric bushing will be normally under the control 65 of the timed mechanism, an auxiliary actu-

ating device urging the eccentric bushing in one direction at a speed greater than that of the timed mechanism and normally restrained by said timed mechanism, means controlled by the advance of a sheet to release the disengageable connection and thereby permit the auxiliary actuating device to shift the eccentric bushing quickly and to move the extensible connection independently of the movement of the member under the control of the timed mechanism, and means for again restoring the disengageable connection.

81. In a sheet feeding machine, the combination with a sheet support and a combing wheel, of means for raising and lowering the combing wheel comprising, an eccentric bushing for the combing wheel, timed mechanism including a member having a reciprocating movement, a slidable connection between the eccentric bushing and the reciprocating member aforesaid, a disengageable connection between the reciprocating member and the slidable connection whereby the movement of the eccentric bushing will be normally under the control of the timed mechanism, a lifting actuator constantly acting on the eccentric bushing to turn the same at a speed greater than that of the timed mechanism normally restrained by the timed mechanism, means controlled by the advance of a sheet for releasing the disengageable connection to thereby permit the lifting actuator to shift the eccentric bushing quickly and to move the extensible connection independently of the movement of the reciprocating member, and means for restoring the disengageable connection to its holding position.

82. In a sheet feeding machine, a sheet support, a combing device, an eccentric mounting for the combing device, power means for shifting the eccentric mounting, a telescoping connection between the power means and the eccentric mounting, a releasable connection in the telescoping connection, means actuated by the advanced sheet for operating the releasable connection, means acting on the eccentric mounting to turn the same when the releasable connection is operated, and means for again restoring the releasable connection.

83. In a sheet feeding machine, a combing device, an eccentric mounting for the combing device, a lifting actuator acting on the eccentric mounting to shift the same to lift the combing device, means normally restraining the action of the lifting actuator, a releasing member, a fulcrum against which the releasing member may act to disconnect the restraining means to permit the lifting actuator to become operative, and means controlled by the advancing sheet for positioning the fulcrum in the path of the releasing member.

84. In a sheet feeding machine, a combing device, an eccentric mounting for the combing device, a lifting actuator acting on the eccentric mounting to shift the same to lift the combing device, means normally restraining the acting of the lifting means, a stationary abutment, a releasing member, a movable filling block controlled by the advancing sheet for positioning the filling block in the path of the rotary member whereby said rotary member will carry the filling block into contact with the stationary abutment to form a fulcrum against which the rotary member may act to disconnect the restraining means to thereby permit the lifting actuator to become operative.
85. In a sheet feeding machine, a sheet support, a combing device, timed mechanism for controlling the raising and lowering of the combing device at regular intervals, an extensible connection between the timed mechanism and the eccentric mounting, a releasing device in the said connection, a lifting actuator connected with the eccentric mounting exerting force to turn the eccentric mounting to raise the combing device, sheet-actuated mechanism for operating the releasable device, to thereby permit the lifting actuator to operate the eccentric mounting independently of the control of the timed mechanism, and means for restoring the releasable device in the extensible connection to its holding position.
86. In a sheet feeding machine, a sheet support, a combing device, an eccentric mounting for the combing device, a lifting actuator acting on the eccentric mounting to turn the same to lift the combing device, a reciprocating member, a hook connected with the eccentric mounting, the reciprocating member having a movement in one direction to engage with said hook after the eccentric mounting has been shifted and having a movement in the opposite direction after said hook has been so engaged to turn the eccentric mounting back to lower the combing wheel.
87. In a sheet feeding machine, a sheet support, a combing wheel, an eccentric mounting for the combing wheel, a lifting actuator exerting a constant force on the eccentric mounting to turn the same to raise the combing wheel, a reciprocating member, a member slidingly engaged with the reciprocating member and having connection with the eccentric mounting, a hook carried by the sliding member arranged to normally interlock with a part on the reciprocating member, and a sheet-actuated mechanism for releasing the hook aforesaid from engagement with the interlocking part on the reciprocating member.
88. In a sheet feeding machine, a sheet support, a combing wheel frame pivotally supporting at one end, a combing wheel mounted in the free end of the frame, a relatively stationary support, a normally inoperative supporting member carried by the combing wheel frame, means for raising the combing wheel in the combing wheel frame, and means for simultaneously throwing the supporting member on the frame into engagement with the relatively stationary support.
89. In a sheet feeding machine, a sheet support, a combing wheel frame pivotally supported at one end, a combing wheel mounted in the free end of the frame, a relatively stationary rack, a supporting pawl carried by the frame, means for normally holding said pawl out of engagement with the rack, means for raising the combing wheel in the combing wheel frame, and means for simultaneously throwing the supporting pawl into engagement with the relatively stationary rack.
90. In a sheet feeding machine, a sheet support, a combing device, a frame in which the combing device is mounted, the said frame being supported by the combing device when the same is in engagement with the sheets on the support, a relatively stationary support, a supporting member carried by the frame and arranged for engagement with the relatively stationary support, means for holding said supporting member out of engagement with the stationary support when the combing device is in engagement with the sheets, means for raising the combing device in the frame, and means for simultaneously throwing the supporting member into engagement with the relatively stationary support.
91. In a sheet feeding machine, a sheet support, a combing wheel frame pivotally supported at one end, a combing wheel mounted in the free end of the frame and arranged when in engagement with the sheets to support the said free end of the frame, a relatively stationary rack, a supporting dog carried by the frame, means for normally holding said dog out of engagement with the rack, means for raising the combing wheel in the combing wheel frame, and means for simultaneously throwing the supporting dog into engagement with the relatively stationary rack whereby to support the combing wheel frame when the combing wheel has been lifted in the frame.
92. In a sheet feeding machine, a sheet support, a movable combing frame, a combing device mounted in the frame, a relatively stationary rack, a supporting dog carried by the frame, means for raising the combing wheel in the frame, a movable member connected with the supporting dog to normally hold the same out of engagement with the rack and arranged when the combing wheel is raised to release the supporting dog, and means for throwing the supporting dog into engagement with the relatively stationary rack.

engagement with the rack when the same has been raised as aforesaid.

93. In a sheet feeding machine, a sheet support, a combing wheel frame, a combing wheel carried by the frame, an eccentric mounting for the combing wheel, timed mechanism for turning the eccentric mounting, two members, one connected to the timed mechanism and the other to the eccentric mounting, a releasably connection between the said two members, a lifting actuator acting on the eccentric mounting to turn the same to raise the combing wheel, a relatively stationary rack, a supporting dog on the frame, means carried by one of the members aforesaid to normally hold the supporting dog out of engagement with the rack, sheet-controlled mechanism for operating the releasable connection to permit the lifting actuator to turn the eccentric mounting, and means for throwing the supporting dog into engagement with the rack when the lifting actuator is thus operated to raise the combing wheel.
94. In a sheet feeding machine, a combing wheel frame pivotally mounted at one end, a combing wheel carried in the free end of the frame, an eccentric mounting for the combing wheel, a lifting actuator acting on the eccentric mounting to turn the same to raise the combing wheel, timed mechanism including a reciprocating member and an extensible connection between the said member and the eccentric mounting, a sheet-controlled releasable connection between the reciprocating member and the extensible connection, a relatively stationary rack, a supporting dog carried by the combing wheel frame, a rod connected to the supporting dog, a cam surface on the extensible connection normally engaging with said rod to hold the dog out of engagement with the relatively stationary rack, and means for throwing the supporting dog into engagement with the rack when the extensible connection has been shifted due to the actuation of the releasable connection.
95. In a sheet feeding machine, a sheet support, a frame pivotally supported at one end, a combing device mounted in the free end of the frame, a supporting dog carried in the free end of the frame, a relatively stationary rack with which said dog is arranged to engage, a controlling rod connected to the supporting dog, a movable member having a cam surface arranged to engage said rod to normally hold the supporting dog out of engagement with the rack, and means for throwing the supporting dog into engagement with the rack when the cam surface on the movable member has been shifted out of engagement with the controlling rod.
96. In a sheet feeding machine, a sheet

support, a combing wheel frame pivotally mounted at one end, a combing wheel mounted in the free end of the frame, a supporting dog carried in the free end of the frame, a relatively stationary rack with which the supporting dog is arranged to engage, means for raising the combing wheel in the frame, and means for simultaneously throwing the supporting dog into engagement with the relatively stationary rack.

97. In a sheet feeding machine, a sheet support, combing mechanism adjustable longitudinally of the support, a rockshaft controlling operation of said combing mechanism and adjustable with the combing mechanism, a lift-bar extending longitudinally of the sheet support, mechanism for raising and lowering said lift-bar, and a connection from the rockshaft adapted to rest upon the lift-bar so as to be operated thereby.

98. In a sheet feeding machine, a sheet support, a combing device, a lifting actuator exerting a force to normally raise the combing device, restraining means normally restraining the lifting actuator, and means for releasing said restraining means comprising, a stationary abutment, a rotating gear, a filling block, and means actuated by the advanced sheet for positioning the filling block in the path of the rotating gear whereby the gear will carry the filling block into engagement with the stationary abutment to form a fulcrum against which the rotating gear may act to release the restraining means.

99. In a sheet feeding machine, a sheet support, a combing device, a lifting actuator exerting its force to raise the combing device, means normally restraining the action of the lifting actuator, a releasable connection forming part of the restraining means, and means for operating the said releasable connection comprising, a rotating gear, a filling block, means arranged to be actuated by the advance of a sheet connected with said filling block for positioning the same in the path of the rotating gear, and a relatively stationary abutment against which the filling block is carried by the rotating gear, the said stationary abutment having an inclined face arranged when engaged by the filling block to force the filling block into more intimate mesh with the gear and the abutment face at the terminus of the inclined face.

100. In a sheet feeding machine, a sheet support, longitudinal supports at the sides of the sheet support, a carriage longitudinally adjustable on said longitudinal supports, the said carriage including a pair of transversely extending operating shafts, and a combing wheel frame supported on said operating shafts and adjustable trans-

versely thereon, a longitudinal drive shaft at the side of the sheet support, gearing connections between said drive shaft and one of the transverse operating shafts for rotating said operating shaft irrespective of the longitudinal adjustment of the carriage, oscillating means for the other of the operating shafts, adjustable connections between the oscillating means of the operating shaft for oscillating the said means irrespective of the longitudinal adjustment of the carriage, gearing from the rotary operating shaft of the combing wheel for driving the same, and means operated by the oscillating shaft for controlling the raising and lowering of the combing wheel with respect to the sheet support.

101. Combing mechanism comprising an operating shaft, an arm pivoted on said shaft, a combing shaft journaled in the free end of the arm, gearing between the operating shaft and the combing shaft, an eccentric bushing loosely mounted on the combing shaft, a combing wheel journaled on the eccentric bushing, a driving member on the combing shaft, a pin and slot connection between said driving member and the combing wheel, a lifting actuator constantly acting on the eccentric bushing to turn the same to raise the combing wheel, means normally restraining the action of said lifting actuator, a releasable connection in said restraining means, a gear on the combing shaft, and a rotating member for operating the releasable connection driven by the gear on the combing shaft.

eccentric bushing to raise and lower the combing wheel.

30

102. Combing mechanism comprising an operating shaft, an arm pivoted on said shaft, a combing shaft journaled in the free end of the arm, gearing between the operating shaft and the combing shaft, an eccentric bushing loosely mounted on the combing shaft, a combing wheel journaled on the eccentric bushing, a driving member on the combing shaft, a pin and slot connection between said driving member and the combing wheel, a lifting actuator constantly acting on the eccentric bushing to turn the same to raise the combing wheel, means normally restraining the action of said lifting actuator, a releasable connection in said restraining means, a gear on the combing shaft, and a rotating member for operating the releasable connection driven by the gear on the combing shaft.
